(57) **CLAIM**

The ornamental design for a vehicle entertainment system, as shown and described.

DESCRIPTION

FIG. 1 is a front perspective view of a vehicle entertainment system with the video monitor in a storage position showing my new design, wherein the dashed lines are used for illustrative purposes only and form no part of the claimed design.

FIG. 2 is a rear perspective view thereof with the video monitor in a storage position, wherein the dashed lines are used for illustrative purposes only and form no part of the claimed design.

FIG. 3 is a rear perspective view thereof with the video monitor in a use position, wherein the dashed lines are used for illustrative purposes only and form no part of the claimed design.

FIG. 4 is a front perspective view thereof with the video monitor in a use position, wherein the dashed lines are used for illustrative purposes only and form no part of the claimed design; and,

FIG. 5 is a front perspective view thereof with the video monitor in a slightly rotated use position, wherein the dashed lines are used for illustrative purposes only and form no part of the claimed design.
